POWER PLANT INSTALLATION

William H. Clayton, Windsor, and Williburt W. Schroeder, West Hartford, Conn., assignors to Combustion Engineering, Inc., Windsor, Conn., a corporation of Delaware

Filed Dec. 27, 1961, Ser. No. 162,330
3 Claims. (Cl. 122—479)

This invention relates generally to a power plant that is comprised of a vapor generator-turbine unit or combination and has particular relation to such a power plant unit operating on the double reheat cycle.

In accordance with the invention there is provided an improved method of operating and an improved organization of such a double reheat power plant system wherein the high pressure and the low pressure reheat temperatures are controlled by a combination of control effects or operations organized in a manner and with relation to the system arrangement to realize optimum operating results from each of these controls. In the double reheat cycle with which the invention is concerned the heat requirements of the high pressure and the low pressure reheats vary relative to each other with varying load. It is desired that the two reheat temperatures, i.e., the high pressure and the low pressure reheat temperatures, as delivered to the intermediate and low pressure turbine stages or sections, respectively, be maintained at a desired and generally constant value throughout the operating load range of the unit. Because of the aforementioned characteristic of the two reheats it is necessary to provide specific controls to effect this result. With the present invention the control of the two reheat temperatures is effected primarily by different control actions and as a result of which the reheat temperatures are maintained at their desired value.

This is achieved by arranging the high pressure and low pressure reheat surface relative to each other in the vapor generator in a manner so that gas recirculation control has its greatest and primary effect on one of the reheats, preferably the high pressure reheat, while the adjusting of the zone of combustion in the furnace has its primary or greatest effect on the other reheat, preferably the low pressure reheat. Through this arrangement and method of operating the two reheat temperatures are controlled throughout the load range over which the unit is operated or at least a major portion of this load range.

Accordingly it is an object of the present invention to provide an improved power plant system wherein the vapor generator-turbine unit is organized to operate on the double reheat cycle and wherein the two reheat temperatures are controlled over a substantial load range.

A still further object of the invention is to provide such an improved power plant system wherein control of two reheats is effective through a combination of gas recirculation type of control and the control produced by adjustment of the zone of combustion in the furnace.

Other and further objects of the invention will become apparent to those skilled in the art as the description proceeds.

With the aforementioned objects in view, the invention comprises an arrangement, construction and combination of the elements of the inventive organization in such a manner as to attain the results desired as hereinafter more particularly set forth in the following detailed description of an illustrative embodiment, said embodiment being shown by the accompanying drawings wherein:

FIG. 1 is a diagrammatic representation in the nature of a vertical sectional view through a high capacity vapor generator-turbine power plant organized in accordance with the present invention;

FIG. 2 is a graphical representation illustrating the con-

2

trol effect obtained by adjusting the zone of combustion in the furnace;

FIG. 3 is a similar graphical representation illustrating the control effect obtained with gas recirculation control;

5 FIG. 4 is a graphic illustration of the heat absorption characteristics of the two reheats of the double reheat organization of the invention under one preferred operating cycle; and

FIG. 5 is a similar graphic representation of the heat 10 absorption characteristic of the two reheats under a modified cycle of operation.

Referring now to the drawings, wherein like reference characters are used throughout to designate like elements, the illustrative and preferred embodiment of the invention 15 includes the furnace 10 into which fuel and air are introduced by the burners 12 with the fuel being burned in the furnace and the combustion gases thus generated passing up through the furnace and through the lateral outlet at the upper end from which extends the horizontally directed gas pass 14 that is, in turn, connected with the downwardly extending gas pass 16. This latter gas pass extends downward in parallel, spaced relation with the furnace and the combustion gases egressing from the furnace and after traversing the horizontal gas pass 14, are directed down through this vertical gas pass and out the outlet 18 to a suitable air heater and stack or other conventional equipment.

The primary fluid of the vapor generator is first introduced into and passed through the economizer 20 with this fluid being supplied to the economizer through a suitable feed pump means, not shown. From the economizer the primary fluid is conveyed to the chamber 22 through the conduit 24. From this chamber 22 the fluid passes down through the conduit 26 into which is connected the pump 28 and from pump 28 the primary fluid enters the headers 30 at the lower end of the furnace. Connected with these headers 30 are tubes 32 which line the walls of the furnace, with the furnace preferably being generally rectangular in transverse section and with the tubes 32 extending upwardly along the inner surface of the furnace walls and connecting with suitable headers 34 at their upper ends. From the header 34 the primary fluid is conveyed to the chamber 22 as through conduit 36. From this chamber 22 primary fluid is conveyed to the heat exchange section 38 through conduit 40 and from this heat exchange section 38 the primary fluid is finally conveyed through conduit 42 to the high temperature vapor heating section 44 of the primary circuit of the vapor generator. After traversing this heat exchange section 44 the primary vapor is heated to its desired temperature and it is then 45 conveyed to the high pressure stage or section 46 of the turbine machine designated generally 48 with the vapor being conveyed through conduit 50.

From the high pressure stage 46 of the turbine the 50 vapor is conveyed through conduit 52 to the low temperature section 54 of the high pressure reheater. After being partially reheated in this section 54 the high pressure reheat vapor is conveyed through conduit 56 to the high temperature stage 58 of the high pressure reheater and from this high temperature stage the reheat vapor is conveyed through conduit 60 to the intermediate stage 62 of the turbine.

The vapor is reheated a second time by being conveyed 65 through conduit 64 to the low pressure reheater 66. After being reheated to its desired temperature this low pressure reheat vapor egresses from this heat exchanger 66 and is conveyed to the inlet of low pressure turbine stage 68 through the conduit 70. The exhaust from this low pressure stage is conveyed to the usual condenser and thence to the condensate system which is conventionally found 70 in vapor generator-turbine units to which the invention pertains.

As previously mentioned the heat requirement of the high pressure and the low pressure reheat vary as the load on the unit changes. With the invention the general characteristic prevails that as the load decreases from maximum the percentage of heat absorbed required by the high pressure reheat vapor necessary to maintain this reheat vapor at its desired, generally constant, temperature throughout the load range increases relative to the heat requirement of the low pressure reheat in order to maintain the temperature of this low pressure reheat vapor at its desired, generally constant, temperature throughout the load range. Accordingly, in order to insure that the temperature of the high and the low pressure reheat vapor will be maintained as desired it is necessary to provide control means to effect this result.

While the aforementioned general characteristic with regard to the relative heat absorption requirements of the low pressure and the high pressure reheat prevail with the invention, in one preferred embodiment of the invention the particular heat requirement characteristics of the reheat is of the nature depicted in FIG. 4 wherein, of the total heat absorption of the unit both the high pressure and the low pressure reheat have an increasing heat absorption characteristic, i.e., with relation to the total, the percentage of heat absorption of these two reheat increases as the load decreases from its maximum value, with the increase of the high pressure reheat being substantially greater or at an increased rate relative to that of the low pressure reheat. This is shown in the FIG. 4 curves wherein the slope of the high pressure reheat curve is much greater than that of the low pressure reheat curve.

A modified arrangement and process of the invention with a somewhat different characteristic is provided with this modified operation being graphically illustrated in FIG. 5. In this modified arrangement the high pressure reheat has a rising heat absorption characteristic with decreasing load while the low pressure reheat has a decreasing heat absorption characteristic with decreasing load. This is evident from the FIG. 5 plot wherein load is plotted against the percent of heat absorption with relation to the total and wherein the high pressure reheat curve has a rising slope as the load is decreased and the low pressure reheat has a falling or downward slope.

The characteristics thus graphically illustrated in both FIGURES 4 and 5 are a result of the particular turbine hookup and design as incorporated into the power plant system.

In accordance with the invention a combination of gas recirculation control and control by means of varying the zone of combustion in the furnace is provided and two reheat are arranged in a manner so that the temperature of each may be regulated throughout a desired load range through the action of these control systems.

Adjustment of the zone of combustion within the furnace is preferably achieved by means of firing the furnace through tilttable burners which may be arranged symmetrically about the furnace walls at locations in the burner zone and so as to direct fuel and air tangent to an imaginary vertical, centrally located cylinder with respect to the furnace thereby creating a whirling mass of burning fuel in the furnace. Such a firing arrangement which will provide for adjustable variation of the combustion zone with respect to the outlet of the furnace is disclosed in U.S. Patent No. 2,575,885 of November 20, 1951. In the illustrative arrangement of FIG. 1 the tilttable burners or burner nozzles are designated generally 72 and they may be pivoted so as to vary the combustion zone. It will be understood that other means of adjustably varying the zone of combustion toward or away from the furnace outlet may be utilized such as providing burners in the furnace throughout the vertical extent of adjustment of the combustion zone and controlling the number and location of the burners that are in operation.

The effect of moving the zone of combustion from a

region away from the furnace outlet toward the outlet or, in the illustrative arrangement moving the zone of combustion upwardly from zone A toward zone B, is to increase the temperature of the gases in the upper portion of the furnace and leaving the furnace with an opposite effect being realized by the opposite adjustment of the zone of combustion.

The control effect that is obtained by means of varying the zone of combustion in the furnace is greatest near the furnace outlet and becomes progressively less at locations further downstream relative to gas flow from the furnace outlet. Accordingly, in the arrangement disclosed the effect of varying the zone of combustion will be greatest on the heat exchange sections 58 and 65 and will become progressively less on the heat exchange sections 38, 54 and 20. This is graphically illustrated in FIG. 2 wherein it is shown that the effect on the high pressure reheat is high while that on the low pressure reheat is somewhat lower and that on the economizer is still lower. Of course the effect of elevating the zone of combustion in the furnace will cause a decrease in the percentage of heat absorption in the furnace.

The gas recirculation control which forms part of the invention includes the gas recirculation fan 74 which is connected to the lower region of gas pass 16 through duct 76 and has its outlet connected with the lower region or hopper of furnace 10 through ducts 78.

In contrast to the effect of adjusting the zone of combustion in the furnace, the gas recirculation type of control has its maximum influence or effect on heat exchange surface located most remote in a downstream gas flow direction from the furnace outlet. Accordingly by introducing combustion gases into the furnace the heat pick-up of the economizer is increased to the greatest extent while the heat pick-up of each of the heat exchange surfaces progressively upstream of the economizer is increased to a progressively lesser extent. This is illustrated in the FIG. 3 set of curves which show that the percentage of change of heat absorption effected by gas recirculation is greatest on the economizer in the illustrative organization of FIG. 1, is somewhat less on the high pressure reheat and is still less on the low pressure reheat. Since the effect of the gas recirculation control as employed with the invention is to decrease the heat absorption in the furnace, this heat absorption will fall as depicted in FIG. 3.

FIGS. 2 and 3, respectively, show the over-all effect of gas recirculation control and the control achieved by adjusting the zone of combustion in the furnace on the low pressure and the high pressure reheat. In order to obtain this characteristic it is necessary that the high pressure reheat be influenced predominately by the low temperature portion 54 of the high pressure reheat so that, of the total heat absorption of the high pressure reheat, a major portion is provided or obtained by this low temperature heat exchange section 54. Thus the high pressure reheat is effectively downstream with relation to combustion gas flow of the low pressure reheat wherefore the high pressure reheat may be advantageously controlled by gas recirculation and the low pressure reheat may be advantageously controlled by adjustment of the zone of combustion longitudinally of the furnace. Since gas recirculation control is most effective at a location remote from the furnace outlet while adjustment of the zone of combustion is most effective at a location close to the furnace outlet the control of the high pressure and low pressure reheat temperatures that is obtained by means of the present invention may be more sensitive by spacing the high pressure and the low pressure reheat from each other along the combustion gas flow path and providing additional heat exchange surface intermediate the location of the high pressure and low pressure reheat. Thus there is provided intermediate the low pressure reheat 66 and the large low temperature portion of the high pressure reheat 54 the primary heat exchange sur-

face 38. By arranging the heat exchange surface in the manner set forth the effective location of the low pressure reheat in the gas stream is close to the furnace outlet while the effective location of the high pressure reheat is well downstream of the low pressure reheat with primary heat exchange surface being interposed between these two locations.

It will be appreciated that the high pressure reheat is divided into a low temperature section of high heat absorbing capacity and a high temperature section of much smaller heat absorbing capacity for the reason that with the predominate portion of the heat absorption of the low pressure reheat being provided at a downstream location the temperature of the combustion gases at this location are sufficiently low so that it is necessary to provide a section of the high pressure reheat in a location of the gas stream having a high temperature in order that the desired high final high pressure reheat temperature may be realized. While the high temperature section 58 of the high pressure reheat is illustrated as disposed upstream relative to gas flow of the low pressure reheat 66 this disposition of these heat exchange surfaces may be reversed. In such a case a somewhat larger high temperature section of the high pressure reheat will be required in order to give the desired final temperature for the high pressure reheat vapor but an improvement in the control will be realized in that the high pressure reheat will become even more predominately responsive to gas recirculation control and the low pressure reheat will become even more predominately responsive to the control obtained by adjustment of the zone of combustion in the furnace.

Since with the method and organization of the invention the heat absorption of the low pressure reheat is changed to a much greater extent than that of the high pressure reheat by adjustment of the zone of combustion in the furnace while the heat absorption of the high pressure reheat is influenced or changed to a much greater extent than that of the low pressure reheat by the introduction of combustion gases into the furnace through the gas recirculation system the low pressure reheat temperature and the high pressure reheat temperature may be regulated and maintained at their desired value with varying load through the combined adjustment of the zone of combustion and adjustment of the recirculation of combustion gases. The control of these reheat temperatures through these control effects may be automatically obtained with FIG. 1 diagrammatically illustrating an arrangement for achieving this result and wherein there is provided temperature sensing device 80 which responds to the temperature of the low pressure reheat vapor leaving the low pressure reheat 66 and being conveyed to the low pressure stage 68 of the turbine machine 48. This device 80, through a suitable controller 82 which is interconnected with the control devices 84 is effective to regulate the angular disposition of the nozzles 72 and accordingly adjust the zone of combustion longitudinally in the furnace toward and away from the furnace outlet. The temperature of the high pressure reheat vapor passing through the conduit 60 to the intermediate stage 62 of the reheat is sensed by the temperature sensing device 86 which is effective to regulate the damper 88 through the action of controller 90 and the operating device 92. Through these controls the temperature of the two reheats may be regulated as the load varies to maintain the two reheat at a desired or predetermined temperature.

Since the high pressure reheat has a greater percentage change of the heat absorption than the low pressure reheat, as evidenced by FIGS. 4 and 5, and since the gas recirculation control provides a somewhat greater control effect than adjustment of the zone of combustion the preferred arrangement is to have the high pressure reheat downstream of the low pressure reheat in the convection gas pass with regard to gas flow, with this

arrangement being disclosed in FIG. 1. While this is the preferred arrangement because a more effective utilization of the two controls or control operations may be had, the invention comprehends an inverse arrangement wherein the high pressure reheat is upstream of the low pressure reheat in the convection gas pass and wherein the temperature of the high pressure reheat is influenced predominately by adjustment of the zone of combustion and the temperature of the low pressure reheat is influenced predominately by the recirculation of combustion gases to the furnace. In this inverse arrangement the temperature of the high pressure reheat will be effectively controlled by adjustment of the zone of combustion in the furnace while the temperature of the low pressure reheat will be effectively controlled by regulation of recirculation of combustion gases to the furnace.

In the FIG. 4 arrangement or modification the operation will be such that at maximum load on the vapor generator 20 the zone of combustion will be at its lowered range of adjustment in the furnace and there will be little if any combustion gases recirculated through the combustion gas system. It may be of advantage to pass just enough gases through the combustion gas recirculation system in 25 order to insure that there is not reverse flow through this system and in order to maintain the various elements of the system at their operating temperature. With the unit thus operating at maximum load the high pressure and the low pressure reheat temperatures are at their desired value 30 as for example 1100° F. As the load on the vapor generator-turbine unit decreases the high pressure and the low pressure reheat temperatures will tend to fall from their desired value. To offset this effect the zone of combustion in the furnace is progressively moved toward the 35 furnace outlet having a predominate effect on the low pressure reheat temperature in the illustrative organization and the quantity of gas recirculated to the furnace 10 is progressively increased influencing predominantly the high pressure reheat temperature with the two control actions being such as to maintain the two reheats at their desired value. Through this operation and system the two reheat temperatures may be maintained at their predetermined value throughout a substantial load range.

In the FIG. 5 arrangement or modification the operation 45 will be such that at maximum load on the vapor generator the zone of combustion will be at its upper range of adjustment in the furnace or at an adjustment well above the lower range even if not at the extreme upper limit of the range of adjustment and as in the case of the FIG. 4 arrangement little if any combustion gases will be recirculated to the furnace through the combustion gas system. Here again it may be advantageous to pass just enough gas 50 through the combustion gas system to insure that inverse flow through the system is not had and that the various elements of the system are maintained at their desired operating temperature. With the unit thus operating at maximum load the high pressure and the low pressure reheat temperatures are at their desired value, as for example, 1100° F. As the load on the vapor generator-turbine unit decreases the amount of combustion gases 55 recirculated to the furnace is progressively increased and the zone of combustion is progressively moved away from its uppermost extreme position or the extreme position closest to the furnace outlet toward the extreme position most remote from the furnace outlet. Through this combination of gas recirculation control and adjustment of the zone of combustion the two reheat temperatures are maintained at their desired value throughout a substantial load range as the load decreases from its maximum or 100 percent rating.

Since the invention is concerned with regulating the two reheat temperatures in a vapor generator-turbine unit operating on the double reheat cycle and since the regulation of the primary vapor temperature does not form a 75 part of this invention this latter regulation has not been set

forth although it will be appreciated that the primary vapor delivered to the high pressure turbine 46 through conduit 50 is maintained at its desired value throughout the operating load range and the regulation of this primary vapor temperature may be effected through any desired known means such as desuperheating or bypass dampers.

Accordingly it will be appreciated that with the present invention the high pressure and the low pressure reheat temperatures in a double reheat unit may be advantageously and effectively regulated and maintained at their desired value throughout a substantial load range with the regulation being obtained by means of regulated actions effected in the furnace and with the organization of the generator being such as to provide optimum temperature regulation of the two reheats.

While we have illustrated and described a preferred embodiment of our invention it is to be understood that such is merely illustrative and not restrictive and that variations and modifications may be made therein without departing from the spirit and scope of the invention. We therefore do not wish to be limited to the precise details set forth but desire to avail ourselves of such changes as fall within the purview of our invention.

What we claim is:

1. In a power plant installation a vapor generator operating in the double reheat cycle, said generator including an elongated furnace having heat exchange tubes on its walls and having a combustion gas outlet, means firing said furnace in a manner such that the zone of combustion may be regulatingly moved toward and away from said outlet, a high pressure and a low pressure reheat means disposed so that combustion gases generated in said furnace pass thereover, means for regulatingly introducing combustion gases which have traversed said reheat means into said furnace at a location such as to increase the heating effect of the combustion gases passing over the reheaters over what it would be without said recirculation, said high pressure and low pressure reheat being positioned in the gas stream so that the control effect obtained by gas recirculation is substantially greater on the high pressure reheat than on the low pressure reheat while the control effect obtained by adjusting the zone of combustion with relation to the furnace outlet is substantially greater on the low pressure reheat than on the high pressure reheat means operative to vary the recirculation of the combustion gases directly and predominantly in accordance with the temperature of the high pressure reheat vapor and means operative to vary the zone of combustion directly and predominantly in accordance with the temperature of the low pressure reheat vapor.

2. A vapor generator operating on the reheat cycle and wherein the vapor generator includes an elongated fluid cooled furnace having a combustion gas outlet adjacent one end, a gas pass extending from said outlet, means firing said furnace at a region remote from the outlet, a high pressure reheat and a low pressure reheat disposed to have the combustion gases generated in the furnace pass thereover with the high pressure reheat being effectively downstream relative to combustion gas flow of the low pressure reheat, means for withdrawing combustion gases from the gas pass at a location downstream of the reheaters and introducing the same into the furnace at a location to increase the heat content of the gases egressing from the furnace, means responsive directly and predominantly to the temperature of the vapor leaving the high pressure reheat effective to adjustably regulate the combustion gases thus introduced into the furnace and means for adjusting the zone of combustion toward and away from the furnace outlet and means responsive directly and predominantly to the temperature of the vapor leaving the low pressure reheat effective to regulate said means for adjusting the zone of combustion.

3. In combination a vapor generator operating on the reheat cycle and including an upright fluid cooled furnace having a combustion gas outlet at its upper region, a gas

pass extending from said outlet, means introducing fuel and air into the furnace at a region remote from said outlet, means introducing recirculated combustion gases into the lower region of the furnace, predominately connection heated high pressure reheat means and predominately connection heated low pressure reheat means in series

5 flow relation with regard to the gas flow with the high pressure reheat means having a portion upstream of the low pressure reheat means and a portion downstream of the low pressure reheat means with the latter portion being of substantially greater heat absorbing capacity than the former portion and disposed so that at least a major portion of the combustion gases produced by the burning fuel in the furnace pass thereover, heat exchange surface forming part of the primary surface of the vapor generator and disposed intermediate the low pressure reheating means and the downstream portion of the high pressure reheat means and means directly and predominantly responsive to the high pressure reheat temperature and operative to 10 15 20 25 30 35 40 45 50 55 60 65 70 75

adjustably control the gases recirculated to the furnace and independently but simultaneously to and directly and predominantly responsive to the low pressure reheat temperature and operative to independently but simultaneously adjustably vary the zone of combustion toward and away from the furnace outlet to provide independent control of the heat input of each of the reheat.

4. In a vapor generator operated on the reheat cycle the improved method comprising introducing and burning fuel in a fluid cooled furnace thereby creating a stream of combustion gases generating high pressure, high temperature vapor by imparting a portion of the heat evolved by the burning fuel to a working medium, passing said high pressure, high temperature vapor to a working zone and utilizing a portion of the energy thereof, reheating this vapor a first time by passing it in heat exchange relation with the combustion gas stream, conveying this reheated vapor to a working zone and utilizing a further portion of the energy thereof, thereafter again reheating said vapor by passing it in heat exchange relation with the combustion gas stream and conveying this reheated vapor to a working zone, imparting at least a predominate portion of the heat for said first reheating of the vapor to the vapor at a location of the combustion gas stream downstream of the location of the second reheating of the vapor, controlling the temperature of the first reheat by regulating the recirculating gases into the furnace directly and predominantly in response to this temperature and simultaneously controlling the temperature of the second reheat by adjusting the zone of combustion in the furnace with relation to the furnace outlet directly and predominantly in response to this last named temperature.

5. The method of operation of claim 4 wherein the cycle of operation is such that both of the reheat have a characteristic of increasing percentage of the total heat absorption with decreasing load with the increase of the high pressure reheat being at a greater rate than the low pressure reheat and wherein the zone of combustion is moved in a direction to increase the temperature of the gases leaving the furnace and the recirculation of combustion gases is increased as the load is decreased to control the two reheat temperatures.

6. The method of claim 4 wherein the cycle of operation is such that of the total heat absorption of the unit the percentage of the first reheat increases as the load is decreased from maximum and that of the second reheat decreases as the load is decreased from maximum and wherein the zone of combustion is moved so as to decrease the temperature of the combustion gases passing from the furnace as the load is decreased from maximum and the recirculation of the combustion gases to the furnace is increased as load is decreased from maximum to control the two reheat temperatures.

7. In a vapor generator operating on the double reheat cycle with the characteristic such that the high and low

pressure reheat temperatures tend to decrease with decrease in load from the maximum and tend to vary relative to each other with variation in load, said generator including a fluid cooled furnace into which fuel is introduced and burned to create a combustion gas stream, the high pressure and low pressure reheaters being disposed in the gas stream, means for recirculating to the furnace combustion gases which have traversed the reheaters and in a manner to increase the heat content of said stream of gases with this increase in heat content having a progressively greater effect on heat exchange surface progressively further downstream in a gas flow sense, and means, independent of the firing rate and operable simultaneously with the gas recirculation, effective to adjustably vary the temperature of the combustion gas stream issuing from the furnace, said reheaters being disposed in said stream so that of the last two named means one of the reheaters is affected predominately by the temperature varying means while the other is affected primarily by the gas recirculation means, means responsive directly and predominately to the temperature of the vapor of said one reheat effective to regulate the means to vary the temperature of the combustion gases issuing from the furnace and means responsive directly and predominately to the temperature of the vapor of said other reheat effective to regulate the recirculation of combustion gases, whereby these vapor temperatures are maintained at their desired value at variation in load.

8. In a vapor generator operating on the double reheat cycle and including a fluid cooled furnace in which fuel is burned creating a combustion gas stream and having the characteristic that of the total heat absorption of the generator the percentage required by the reheaters to main-

tain desired temperature varies relative to each other with varying load, the method of operation comprising effectively imparting heat from said combustion gas stream to the high pressure reheat vapor at one location and to the low pressure reheat vapor at another location spaced in a combustion gas flow sense from said one location, simultaneously providing a pair of control actions effective to independently control the two reheat temperatures relative to each other with varying load including regulatingly introducing into the furnace combustion gases that have traversed the reheat and in a manner to increase the heat content of the gas stream over what it would otherwise be and, in addition thereto and independent of the firing rate, regulatingly adjusting the temperature of the stream of combustion gases egressing from the furnace, the relative disposition of the two reheat in the gas stream being such that the introduction of combustion gases into the furnace has a greater effect on one of the reheat than the other while varying the temperature of the combustion gases has a greater effect on said other than said one reheat, sensing the temperature of the vapor of said one reheat and directly and predominately in response thereto regulating the introduction of combustion gases into the furnace to maintain this vapor temperature at its desired value and sensing the temperature of said other reheat and directly and predominately in response thereto regulating the temperature of the combustion gas stream egressing from the furnace to maintain this vapor temperature at its desired value.
